Fig. 1

Fig. 6

The diagram illustrates a radio receiver circuit with a mechanical switch mechanism. The circuit is powered by a battery with terminals **I**, **II**, and **III**. The receiving apparatus (1) is connected to terminal **I** and ground. The circuit includes a vacuum tube stage (18) with grid 19, a variable capacitor (20, 21), and a coil (22). A second vacuum tube stage (23) with grid 24 is connected to the output of the first stage. The circuit also features two additional vacuum tube stages (26, 27) with grids 29 and 34, and a third stage (31) with grid 36. A power supply section (37) with grid 37 and a filament winding (38) is connected to the circuit. The mechanical part consists of a base (10) with a switch (11), a gear assembly (12, 13, 14, 15, 16, 17), and a dial (18'). The switch (11) is connected to the circuit, and the gear assembly is used for tuning.

SPEED CORRECTION FOR MULTIPLEX TELE-
GRAPH AND FACSIMILE SYSTEMSRichard E. Mathes, Westfield, N. J., assignor to
Radio Corporation of America, a corporation of
Delaware

Application December 13, 1938, Serial No. 245,364

20 Claims. (Cl. 178—53)

This invention relates to speed and phase correction in multiplex telegraphy and facsimile transmission operating on the time division principle. In such systems the rotating connectors or distributor arms at the transmitting and receiving ends must run in absolute synchronism and phase. With distributor arms that are run by electric motors, speed control is usually obtained by means of tuning fork mechanisms at the transmitter and receiver that are as identical as it is possible to make them. These control devices will maintain substantial synchronism between the rotating parts of the transmitter and the receiver but it is practically impossible to maintain with them alone the exact synchronism and phase necessary for satisfactory operation of the system. It is therefore necessary to use some speed correction mechanism that operates to correct any tendency to deviate from the synchronous speed. In my Patent No. 2,038,375, April 21, 1936, I have described mechanism for making this speed correction by utilizing brushes and short-circuiting bars on the rotating mechanism controlling the distributor arm.

It is an object of this invention to correct the speed of motors and other rotating parts without utilizing any brushes and short-circuiting bars for this purpose.

Another object is to combine pulses of the incoming signal with electrical potentials produced by the rotating distributor in such a way that resultant potentials produced by the incoming signal and the rotating parts initiate movements that bring the parts back into synchronism and phase.

Other objects will appear in the following description, reference being had to the drawings in which similar reference characters represent similar parts.

In the drawings:

Fig. 1 is a diagrammatic illustration of one form of my invention.

Fig. 2 is a diagrammatic illustration of a second form of my invention.

Fig. 3 is a diagrammatic illustration of a third form of my invention.

Fig. 4 is a series of graphs illustrating the principle of the speed control in Figs. 2 and 3.

Fig. 5 is a series of graphs showing the torque in the relay of Fig. 1.

Fig. 6 shows the battery connection for applying the voltage to the circuits in Figs. 1, 2 and 3.

Referring to Fig. 1, 1 indicates radio receiving apparatus consisting of the usual tuning devices,

amplifiers, detectors and tone keyers that produce in line 2 separate pulses of current such as are more particularly described in my Patent No. 1,979,484, November 6, 1934. This station equipment is well known and it is sufficient to state that the received signal exists in line 2 in the form of separated current pulses of irregular length and spacing but the beginning and end of each pulse occurs at a definite time in respect to the keying speed. The combined signals in line 2 of the receiver are separated by the distributor arm 3 made to rotate in synchronism with the distributor arm at the transmitter by the electric motor 4 energized in ways well known in the art for maintaining synchronism between the transmitting and receiving distributors. Since any type of control may be used for motor 4 the energizing circuits have not been shown.

The stator frame of the electric motor 4 is geared to speed correction unit 5 so that the frame is moved forward in the direction of rotation when the speed is slow, and in the opposite direction when the speed is fast. In this way the distributor arm 3 is run in absolute synchronism and phase with the distributor arm at the transmitter.

The rotation of the speed correction motor 5 is brought about by a relay 6 which closes the circuit of the motor to the positive or negative terminal. This relay is under the control of two electromagnetic coils. One 7, of the coils is wound around switch tongue 8 and the other one, 9, is wound on the relay field core. The coil 7 is energized by an inductor generator 10 having the rotor 11 attached to the rotating shaft of the distributor arm either directly or by suitable gearing. The field of this inductor generator is supplied by coils 12 connected to the terminals of suitable supply such as the battery 13 in Fig. 6. The armature of the inductor generator consists of coils 14, 15, connected to the relay coil 7 by conductors 16 and 17. The composite signal pulses coming over line 2 are imposed through conductor 18 on the grid of a tube 19, the output of which extends through transformer 20. The secondary of this transformer is connected to ground and to a rectifier 21 of any appropriate kind. Of course the transformer will transmit a brief potential only at the beginning and close of a signal character while the field is building up or collapsing. That is, there will be a pulse generated only at the change of sense of the signals. No potential will be generated while the current is steady. The rectifier 21 is connected through a coupling condenser 22 and leak

50

40

45

55

resistance 22' with the multi-vibrator generally indicated by reference character 23. This rectifier eliminates one of these two pulses; for example, the one at the end of each signal character. This multi-vibrator is of the type described by Abraham and Bloch in "An. d. Physique XII," page 252, 1919. It is essentially an oscillator maintaining a frequency that bears a constant ratio to the rate of rotation of the distributor arm at the transmitter. While this multi-vibrator is old and well known in the art, its method of operation is somewhat obscure and it, therefore, will be described somewhat in detail.

When the potentials of the battery 13 are first applied to the terminals 24, 25, each condenser 26 and 27 will commence to charge. Condenser 27 will be charged by current flowing from terminal 24 through one-half of coil 9 to conductor 28, resistance 29, condenser 27, grid resistance 30, to ground terminal 25. The other condenser will charge through conductor 31, plate resistance 32, condenser 26, grid resistance 33, to ground terminal 25. It will thus be seen that the charging current from each condenser passes through the grid resistances in such a direction as to make the grids positive. This has no effect on this initial charge except to cause the tubes 34 and 35 to draw more current and retard the charging operation somewhat by increasing the drop in resistances 29 and 32.

Theoretically, it would be possible to charge the condensers 26 and 27 to the full line potential of conductors 24, 25, without any oscillating action taking place, but this would require an absolutely steady plate-filament current flowing at all times. It is well known that the plate-filament current of a vacuum tube is not steady even when no adjustments are being made. Therefore, the tubes 34 and 35 will draw slightly varying currents. Suppose that after the condensers are initially charged to some potential, tube 34 has a very slight increase in current. This causes a slight discharge of condenser 26 because the slightly increased drop in plate resistance 32 has lowered the voltage impressed on the condenser below the charge in that condenser. This condenser 26 will discharge through the plate filament circuit of tube 34 through conductor 36, resistance 33, and conductor 37. This flow of current is in such a direction as to place a negative bias on the grid of tube 35. This causes tube 35 to draw less current and condenser 27 commences to charge further because of the lessened drop in plate resistance 29. This charging current will pass through grid resistance 30 and increase the positive bias on the grid of tube 34. This causes that tube to draw still more current which causes condenser 26 to further discharge, due to the increase in drop in plate resistance 32. This further increases the negative bias on grid 35 due to the increased drop in grid resistance 33. This action continues until finally tube 35 blocks and no current at all passes through resistance 29. Condenser 27 then has its maximum charge and condenser 26 its minimum charge.

When condenser 27 obtains its maximum charge, current ceases to flow through grid resistance 30 and the grid of vacuum tube 34 then goes more negative. This reduces the plate current flowing through resistance 32 and condenser 26 commences to charge because the voltage at its terminals is now increased due to the diminished drop in resistance 32. When this condenser starts to charge the current flows through con-

ductor 37, grid resistance 33, conductor 36, to ground terminal 35 and back to the positive terminal 24. It will be seen that this places a positive potential, or less negative potential, on the grid of vacuum tube 35 and the tube starts to draw current. This increases the drop in resistance 29 and the voltage impressed on condenser 27 is then lowered below the voltage of the charge therein. Condenser 27 therefore discharges through the plate filament circuit of tube 35, conductor 38, grid resistance 30 and conductor 39. This makes the grid of tube 34 still more negative due to the drop in resistance 30 and condenser 26 further charges due to decreased drop in plate resistance 32, and this charging current causes tube 35 to draw still more current, as previously explained. This causes condenser 27 to still further discharge. This action continues until tube 34 blocks and a reverse action takes place in respect to the two condensers.

Thus, the unbalance condition of this circuit arrangement causes the multi-vibrator to continue to vibrate or oscillate at a frequency depending upon the charging and discharging times of the condensers which depend upon the constants of the circuits.

The circuits of the multi-vibrator 23 are adjusted so that the frequency of vibration is the same as the frequency of rotation of distributor arm 3 but it seems to be humanly impossible to cause two oscillators or rotating mechanisms to continue indefinitely at absolute synchronism and to cause absolute synchronism, and occasional correction is necessary. To obtain this correction, I cause the rectified pulses of the signal to be applied at 40 to the grid of tube 35. This pulls the multi-vibrator into step and causes it to oscillate at a frequency that is absolutely the same as the frequency of rotation of the transmitter distributor at the sending station. The operation of my improved speed correction system may now be explained.

The inductor alternator 10 is generating an alternating potential of a frequency that is the same as, or proportional to, the rate of rotation of the distributor arm 3. Switch tongue 8 is magnetized by a current of this frequency which passes through coil 7. The field of relay 6 is magnetized by the oscillating current that passes alternately through the two halves of the coil 9 to the multi-vibrator 23. This produces a magnetization in the core 41 which changes its polarity with the frequency of the multi-vibrator.

The inductor 11 is so positioned on the distributor shaft that the magnetization of coil 7 is 90° out of phase with the magnetization of coil 9 produced by the multi-vibrator, which is in phase with the distant transmitter distributor arm. With this adjustment the switch tongue will remain in mid position for reasons that will now be explained.

In Fig. 5 a series of graphs H to L inclusive, show the torque or electromagnetic moment of the relay for various differences of frequencies of the multi-vibrator and the generator 10. For the flux curves a and b, the positive ordinates may be assumed, for purposes of explanation, to indicate north pole polarity for poles 41' and 41'' and negative ordinates south pole polarity. Then for torque curve c positive ordinates indicate repulsion of the tongue pole 41'' away from field pole 41' and negative ordinate movement toward such pole.

Graphs H show the relation for synchronism

between the multi-vibrator and generator 10. Curve *a* indicates the flux in field pole 41' produced by coil 9 and curve *b* gives the flux in the movable pole 41" produced by the coil 7. The relay tongue is so damped, mechanically, that it cannot vibrate at the frequency of the torque indicated by curve *c* which is twice the frequency of the multi-vibrator. Since the average positive and negative torque, so to speak, is zero the relay tongue remains motionless.

In graphs I the torque is shown when the generator 10 lags 45° behind its normal synchronous condition. The average positive torque is greater than the average negative torque and the tongue pole 41" moves away from field pole 41'. 15

In graphs J the torque is shown when the generator 10 is 90° behind the multi-vibrator. Here curves *a* and *b* coincide. The torque shown by curve *c* is all positive and as before, the tongue pole 41" moves away from field pole 41'. Thus, 20 for all lagging conditions from 0 to 90° the switch tongue is forced to the left in Fig. 1 into engagement with the positive contact.

In graphs K the torque is indicated by *c* for 45° lead of the generator 10 over the multi-vibrator. Here the average torque is negative and the tongue pole 41" moves toward field pole 41'. 25

In graphs L the torque is indicated by *c* for 90° lead. Under this condition the torque is all negative and the tongue pole 41" likewise moves toward field pole 41'. It will be apparent that for all leading conditions from 0° to 90° the switch tongue will be forced into engagement with the negative terminal.

The above analysis of conditions between 90 35 lag and 90 lead is merely to show how the relay operates. As a matter of fact the receiving distributor never departs from synchronism but a slight amount. Whenever it lags slightly the switch tongue is thrown into engagement with the positive terminal 42, and current flows through conductor 43 to the correction motor 5 which will rotate the frame of motor 4 in the direction of rotation of the distributor shaft 3. This will speed the shaft up until it gets in phase with the multi-vibrator and distant transmitter distributor arm.

If the distributor arm 3 should slightly speed up, that is, lead, the switch tongue will be thrown into engagement with the negative terminal 44 and the correction motor 5 will be rotated against the direction of motion of switch arm 3. This will slow down the motor until it is again in synchronism with the multi-vibrator. In this way absolute synchronism and phase is maintained by this embodiment of my invention.

In the embodiment of Fig. 2 the distributor arm is driven by the same kind of motor 4, as in Fig. 1, and its speed is corrected by the same sort of motor 5 as in that figure though the control of the speed correction motor is somewhat different. The distributor, either by direct connection or by any type of gearing operates a generator of alternating current shown diagrammatically at 45, which feeds current of frequency *F* through conductors 45' to the primary of transformer 46. The frequency *F* of this generator is the same as the channel keying frequency of the incoming signal. One end of the secondary of this transformer is connected to the center of the secondary of transformer 47 which is connected between the grids of vacuum tubes 48, 49. The other end of the secondary of transformer 46 is connected through resistance 50 to the neutral terminal of the battery 13

through ground. A second generator 51 directly or otherwise connected to the distributor arm 3 produces a voltage having a frequency *F*₁ that is a higher harmonic of frequency *F*. In this embodiment I have made the frequency *F*₁ the sixth harmonic of the frequency *F* as shown in the graphs of Fig. 4, but the invention is not limited to this particular frequency. The output of generator 51 is fed through conductors 51' to the primary of transformer 47.

The plates of tubes 48 and 49 are connected to the positive terminal 52 through coils 53, 54, of a differential relay, the tongue 55 of which is connected to the speed correction motor 5. When tongue 55 moves against the positive contact 56 the motor rotates the field frame of the motor 4 in one direction and when in engagement with contact 57 it rotates the motor 5 and field frame of motor 4 in the opposite direction. Condensers 58, 59, may be arranged to shunt the coils 53, 54, as shown in the drawings, to integrate the pulses and prevent chattering of the relay. The filaments of vacuum tubes 48 and 49 are connected to the neutral point of battery 13 as by grounding.

The incoming signal wire 2 is connected to the distributor arm 3 in the same way as in Fig. 1 and this wire 2 is also connected through a tube 19, transformer 20, conductor 60, rectifier 21 and condenser 22, to the junction point between resistance 50 and the secondary of transformer 46.

The operation of the modification in Fig. 2 is as follows:

The constants of the circuits of generators 45 and 51 are so chosen that their combined voltage is insufficient to operate the relay tongue 55. In Fig. 4, graph F shows the output of generator 45, a half wave only being shown, as this is sufficient for explanation. Graph F₁ represents the voltage of the frequency of generator 51 which in this case is the sixth harmonic of the other frequency. Graph B illustrates the composite voltage produced by the combination of voltages *F* and *F*₁.

In this composite voltage it will be seen that at the center point 62, graph B has the same value as graph F because as shown by graph F₁ the voltage in generator 51 is zero. At point 63 the composite voltage is a maximum 15° to the left of point 62 in this figure. The voltage at point 65 or 64 in the composite curve is of insufficient value to operate relay tongue 55.

Since the grids of tubes 48 and 49 are arranged in opposition as in push pull tube circuits, the plate voltage in one tube is 180° out of phase with that in the other as far as the frequency *F*₁ is concerned, but in phase insofar as frequency *F* is concerned. Therefore, graphs A in Fig. 4 may be taken as applying to one tube, say, tube 48, and graphs C, as applying to the other tube 49. Since frequency *F*₁ is reversed in graphs C, as compared with frequency *F*₁ of graphs A, the maximum value 63' occurs at the right of point 62 in Fig. 4 and the values 64' and 65' are also reversed, as compared to similar points in graphs A. Current led in through line 60 from receiving conductor 2 places a drop in resistance 50 that is impressed on the grids of tubes 48 and 49 in the same phase.

The negative bias 66 and 67 placed on the grids of tubes 48 and 49 is sufficient to block these tubes or to permit only a very small current flow in the plate circuits of the tubes even when the signal pulse 68 of graphs D is combined with the other two currents at the point 62. At this point

the distributor arm 3 is in phase and synchronism with the signal.

If the receiving distributor arm 3 of Fig. 2 happens to depart from synchronism the graphs A and C will move relatively in respect to signal pulse 68 of graphs D. For convenience of illustration this relative movement will be shown by duplicating the signal pulses in graphs D either to the right or left of the center point 62.

In slowing down of arm 3 let it be assumed that the relative movement is such as to place the signal pulse in the position shown at 69 in graphs D. In moving from 62 to point 69 the resultant voltage increases because the signal pulse shown at 69 is combined with the maximum voltage 63 of graph A. Tube 48, therefore, draws current, but the tube 49 is still blocked, its grid voltage being the sum of 63a and 69. The plate current of tube 48 is shown by graph E. This plate current flowing through coil 53 operates the relay tongue 55 which connects the correction motor 5 with the positive terminal 56. The field frame of synchronous motor 4 is then rotated in the direction of rotation of the motor connected to distributor arm 3 and this brings the distributor arm back into phase to the point 62.

If the distributor arm 3 attempts to speed up it will get out of phase in the other direction, as shown by graphs C and D. The signal pulse is now indicated at 70 in line with the hump 63' of combined frequencies FF₁. This produces plate current as shown in graph G which flows through coil 54. Tube 48 is blocked at this time, the combined grid voltage being 63b plus single voltage 70. The tongue 55 is now moved into contact with the negative terminal 57. The correction motor 5 then rotates in the opposite direction and rotates the field frame of the motor 4 opposite to the direction of rotation of the distributor arm 3 and it is brought back into phase at point 62. Thus synchronism is maintained between the transmitter and the receiver without any commutator connections on the distributor shaft.

It will be apparent from an inspection of the graphs in Fig. 4 that the higher the harmonic used, within reason, for frequency F₁, the closer the regulation will be but the sixth harmonic is quite suitable for the purpose.

In Fig. 3 a further modification is shown. In this modification the current from generators of frequency F and F₁ are led into transformers 46 and 47 in exactly the same way as in Fig. 2, but the terminals of the transformer 47 are connected to a multi-vibrator indicated generally at 23 to elongate or fill out the signal pulse coming over conductor 60 before the output of transformer 47 is connected to the tubes 48 and 49. In this way a stronger magnetic pull may be produced by relay coils 53 and 54 through the action of the multi-vibrator. This multi-vibrator is biased so that no current flows in the plate circuit except when the maximum voltage of the crests 63, 63', is impressed on the grids. The multi-vibrator thus does not oscillate continuously but when acting under the voltage crests 63 or 63' it vibrates a number of times, as later explained. In this modification the bias on multi-vibrator tubes 34, 35, is such as to block them even with the peak voltages 63 or 63'.

When the distributor arm is in phase with the signal pulses, the relay tongue 55 remains in neutral position because the multi-vibrator tubes 34, 35, and the relay tubes 48 and 49 are still blocked. When the distributor arm 3 retards in phase through a decrease in speed over the synchronous

speed the relative position of the signal pulse will be indicated at 69 in Fig. 4. The resultant pulse 63 impressed on the grid of one of the tubes, for example, that of tube 35, will cause that tube 5 to draw current, but relay tube 48 will not draw current. The drop in resistance 29 causes condenser 27 to discharge because it has previously been charged at full potential of the line. The charging current will pass through the plate filament circuit of tube 35 to groundup through resistance 50, the primaries of transformers 46, 47, resistance 30 and conductor 39. This instantly places a more negative potential on the grid of tube 49 blocking it still more strongly.

When the signal pulse diminishes tube 35 15 draws less current and condenser 27 starts to charge. This places a strong positive bias on the grid of tube 34 and it starts to draw current. Condenser 26 then starts to discharge and makes 20 the grid of tube 35 still more negative and so on till the peak 63 passes. All of this, of course, happens practically instantaneously and the net result of the peak voltage applied to grid of tube 35 is to make the grid of tube 49, which has the 25 same potential as tube 34, highly positive for a sufficient period to pass a strong current through coil 54. In this case the potentials of the terminals of the relay would be reversed so that coil 54 connects to the positive terminal though, of course, the same result could be accomplished in other ways as by reversing the winding of coils 54 and 53, changing the polarity of motor 5, etc.

After the peak voltage 63 or 63' passes, both 30 tubes of the multi-vibrator block until another of 35 these peaks occurs.

To explain the expression "channel keying frequency" used in the claims, it is explained that the smallest marking unit in a Morse code message is a dot. Since a space is required to distinguish this dot from the other characters, the space immediately following the dot is part of the dot cycle. The number of these dot cycles of a single channel or their equivalent fed through the multiplex system per second is called the "channel keying frequency."

In a multiplex system of the type described, the channel keying frequency of the various channels is the same and the "composite keying frequency" is the sum of all the channel keying frequencies. For example, in a three channel system, if the channel keying frequency is 60 dot cycles per second, the composite keying frequency is 180 dot cycles per second. Both of these terms are used in multiplex telegraphy, but I prefer to use the term "channel keying frequency" 50 in the appended claims. In equal length codes, the channel keying frequency would have the same significance, but in such codes one cycle would be a mark and a space and the channel keying frequency would be the number of such cycles of a channel sent through the multiplex system per second.

I have shown in the drawings one or more 55 dynamos connected to the receiver distributor to run at a speed proportionally thereto but any other form of generator of alternating potential may be used instead, so long as it has a frequency proportional to the frequency of the receiver distributor. Also, in Figs. 2 and 3 the harmonic frequency may be obtained from the generator of the fundamental frequency by using well known frequency changers. Various other modifications may be used without departing from the spirit of the invention.

Having described my invention, what I claim is:

1. In a telegraph system for receiving multiplex signals having a predetermined channel keying frequency, a receiving line, a distributor connected to said line, means for operating said distributor substantially at said channel keying frequency, control means for causing the first means to increase and decrease the speed of said distributor, a generator of alternating electromotive force at the receiver having a frequency proportional to the channel keying frequency, a second generator of alternating electromotive force at the receiver having a frequency proportional to the speed of said distributor and means for causing said control means to increase the speed of the distributor when the frequency of the second generator is below that of the first generator and to decrease the speed when it is thereabove.

2. In a telegraph system for receiving multiplex signals having a predetermined channel keying frequency, a receiving line, a distributor connected to said line, means for operating said distributor substantially at a speed of rotation proportional to said channel keying frequency, control means adapted, when connected to one potential to vary the speed of said distributor in one sense and when connected to another potential to vary the speed in the opposite sense, a generator of alternating current at the receiver having a frequency proportional to said channel keying frequency, a second generator of alternating current at the receiver having a frequency proportional to the speed of said distributor and a relay for connecting said control means to one potential when the frequency of the second alternating generator is below that of the first generator and to the other potential when it is thereabove.

3. In a telegraph system for receiving multiplex signals having a predetermined channel keying frequency, a receiving line, a distributor connected to said line, means for operating said distributor substantially at a speed of rotation proportional to said channel keying frequency, control means adapted, when connected to one potential to vary the operating rate of said distributor in one sense and when connected to another potential to vary the speed in the opposite sense, a generator of alternating current at the receiver having a frequency proportional to said channel keying frequency, a generator of alternating current operated with said distributor having a frequency proportional to the speed of said distributor and a relay for connecting the control means to one potential when the frequency of the second generator is below that of the first generator and to the other potential when it is thereabove.

4. In a telegraph system for receiving multiplex signals of a predetermined channel keying frequency, a receiving line, a distributor connected to said line, an electric motor operating said distributor substantially at a speed of rotation proportional to said channel keying frequency, an oscillator connected to the said line having a frequency proportional to said channel keying frequency, an alternating current generator operated with said distributor having a frequency proportional to said speed and means for rotating the stator of said motor in one direction when the generator frequency is below that of the oscillator and for rotating it in the opposite direction when it is thereabove.

5. In a telegraph system for receiving multiplex signals having a predetermined channel

keying frequency, a receiving line, a distributor connected to said line, an electric motor operating said distributor substantially at a speed of rotation proportional to said channel keying frequency, an electric motor adapted to rotate the stator of the first mentioned motor both with and against the direction of the rotor rotation, an oscillator connected to said line having a frequency proportional to said channel keying frequency, an alternating current generator operated with said distributor having a frequency proportional to said speed and means for causing the second mentioned motor to rotate said stator in the direction of said rotor when the generator frequency is below that of the oscillator and against it when it is thereabove.

6. In a telegraph system for receiving multiplex signals of a predetermined channel keying frequency, a receiving line, a distributor connected to said line, an electric motor operating said distributor substantially at a speed of rotation proportional to said channel keying frequency, an electric motor adapted to rotate the stator of the first mentioned motor in one direction when connected to one potential and in the opposite direction when connected to another potential, an oscillator connected to said line, means for causing the oscillator to operate at a frequency proportional to said channel keying frequency, an alternating current generator connected to said distributor to operate at a frequency proportional to said speed, a relay switch having a coil energized by said generator and another coil energized by said oscillator for connecting the second mentioned motor to one potential when the generator frequency is below that of the oscillator and to connect it to another potential when it is thereabove.

7. In a telegraph system for receiving multiplex signals of a predetermined channel keying frequency, a receiving line, a distributor connected to said line, an electric motor operating said distributor substantially at a speed of rotation proportional to said channel keying frequency, an electric motor rotating the stator of the first mentioned motor in one direction when connected to positive potential and in the opposite direction when connected to negative potential, an oscillator connected to said line, means for causing the oscillator to operate at a frequency proportional to said channel keying frequency, an alternating current generator connected to said distributor to operate at a frequency proportional to the speed of said distributor, a relay switch having a coil energized by said generator and another coil energized by said oscillator for connecting the second mentioned motor to positive potential when the second generator departs in one sense from the frequency of the oscillator and to connect it to negative current when it departs in the opposite sense.

8. In a synchronizing device, a generator of alternating electromotive force, a commutating device having a contact arm and a series of contacts, means to rotate said arm into successive engagement with said contacts substantially at a speed of rotation proportional to the frequency of said generator, a second generator of alternating electromotive force operated by said means at a frequency proportional to the speed of rotation of said arm, the second electromotive force being 90° out of phase with the first electromotive force when the two frequencies are identical, and means energized by both of said generators for causing the first mentioned means

to increase and decrease the speed of rotation of said arm when the frequency of the second electromotive force respectively drops below and rises above that of the other electromotive force.

9. In a synchronizing device, a generator of alternating electromotive force, a commutating device having a contact arm and a series of contacts, means to rotate said arm into successive engagement with said contacts substantially at a speed of rotation proportional to the frequency of said generator, a second generator of alternating electromotive force operated by said means at a frequency proportional to the speed of rotation of said arm, the second electromotive force being 90° out of phase with the first electromotive force when the two frequencies are identical, and electromagnetic means energized by both of said generators for producing a steady torque in one sense when the frequency of the second electromotive force drops below that of the other and a steady torque in the other sense when it rises thereabove, and means controlled by said torque for causing the first mentioned means to vary the speed of rotation of said arm.

10. In a synchronizing device, a generator of alternating electromotive force, a commutating device having a contact arm and a series of contacts, means to rotate said arm into successive engagement with said contacts substantially at a speed of rotation proportional to the frequency of said generator, a second generator of alternating electromotive force operated by said means at a frequency proportional to the speed of rotation of said arm, the second electromotive force being 90° out of phase with the first electromotive force when the two frequencies are identical, a relay having a field coil energized by one generator and an armature having a coil energized by the other generator, said armature being damped to prevent its moving at the standard frequency, and means controlled by said armature for causing the first mentioned means to increase and decrease the speed of rotation of said arm.

11. In a telegraph system for receiving multiplex signals, having a predetermined channel keying frequency, a distributor for receiving said signals, means for operating the distributor substantially at a speed of rotation proportional to said channel keying frequency, a generator of alternating electromotive force, means operated in response to change of sense in the signal characters for keeping the frequency of said generator proportional to said channel keying frequency, a second generator of alternating electromotive force operated with the distributor at a frequency proportional to the speed of rotation of said distributor, the second electromotive force being 90° out of phase with the first electromotive force when the speed of the distributor is proportional to said channel keying frequency and means energized by both of said generators for causing the first mentioned means to increase and decrease the said speed when the ratio of the frequency of the second electromotive force to that of the other electromotive force respectively decreases and increases.

12. In a telegraph system for receiving multiplex signals of a predetermined channel keying frequency, a receiving line, a distributor connected to said line, means for producing unidirectional pulses when a signal character changes in one sense, means for operating the distributor substantially at a speed of rotation proportional to said channel keying frequency, a generator

of alternating electromotive force having a frequency proportional to the speed of said distributor, a second generator of alternating electromotive force having a frequency harmonic to that of the first generator, means energized by the combination of said pulses, and said electromotive forces for causing the second mentioned means to increase said speed when its ratio to said channel keying frequency and to decrease the speed when said ratio increases.

13. In a telegraph system for receiving multiplex signals of a predetermined channel keying frequency, a receiving line, a distributor connected to said line, means for producing unidirectional pulses when a signal character changes in one sense, an electric motor operating the distributor substantially at a speed of rotation proportional to said channel keying frequency, a generator of alternating electromotive force having a frequency proportional to the speed of said distributor, a second generator of alternating electromotive force harmonic to the first electromotive force, means energized by the combination of said pulses, and said electromotive forces for causing said motor to increase the speed of the distributor when its ratio to the channel keying frequency decreases and to decrease the speed when said ratio increases.

14. In a telegraph system for receiving multiplex signals of a predetermined channel keying frequency, a receiving line, a distributor connected to said line, means for producing unidirectional pulses when a signal character changes in one sense, an electric motor operating the distributor substantially at a speed of rotation proportional to said channel keying frequency, a relay having a switch tongue and two contacts of different potentials, means to cause said motor to increase its speed when the switch tongue engages one contact and to decrease its speed when it engages the other contact, a generator of alternating electromotive force having a frequency proportional to the speed of said distributor, a second generator of electromotive force having a frequency harmonic to that of the first electromotive force, means energized by the combination of said pulses, and said electromotive forces for connecting said switch tongue to one of said contacts when the ratio of the speed of the distributor to the channel keying frequency decreases and to the other contact when said ratio increases.

15. In a telegraph system for receiving multiplex signals of a predetermined channel keying frequency, a receiving line, a distributor connected to said line, means for producing unidirectional pulses when a signal character changes in one sense, an electric motor operating the distributor substantially at a speed of rotation proportional to said channel keying frequency, a switch, a positive and negative voltage source, means to cause said motor to increase its speed when the switch connects it to voltage of one polarity and to decrease its speed when it connects it to voltage of opposite polarity, a generator of alternating electromotive force having a frequency proportional to the speed of the distributor, a second generator of electromotive force having a frequency harmonic to that of the first electromotive force, means energized by the combination of said pulses, and said electromotive forces for connecting said switch tongue of one of said contacts when the ratio of the speed of the distributor to the channel keying frequency de-

creases and to the other contact when said ratio decreases.

16. In a telegraph system for receiving multiplex signals of a predetermined channel keying frequency, a receiving line, a distributor connected to said line, means for producing unidirectional pulses when a signal character changes in sense, an electric motor operating the distributor substantially at a speed of rotation proportional to said channel keying frequency, a switch, a positive and negative voltage source, means to cause said motor to increase its speed when the switch connects it to voltage of one polarity and to decrease its speed when it connects it to voltage of opposite polarity, a generator of alternating electromotive force having a frequency proportional to the operating rate of said distributor, a second generator of alternating electromotive force having a frequency that is a sixth harmonic of the first electromotive force and means energized by the combination of said pulses, and said electromotive forces for connecting said switch tongue to one of said contacts when the ratio of the speed of the distributor to said channel keying frequency and to the other contact when said ratio increases.

17. In a telegraph system for receiving multiplex signals of a predetermined channel keying frequency, a receiving line, a distributor connected to said line, means for producing unidirectional pulses when a signal character changes in sense, an electric motor operating said distributor substantially at a speed of rotation proportional to said channel keying frequency, a generator of alternating electromotive force having a frequency proportional to the speed of said distributor, a second generator of alternating electromotive force having a frequency that is a sixth harmonic of that of the first electromotive force, two triodes having their input electrodes connected in parallel to receive said unidirectional pulses and the first electromotive force, and in opposition to receive the second mentioned electromotive force, a relay having one coil in the output circuit of one triode and another coil in the output of the other triode and means energized by said relay for controlling the speed of said motor.

18. In a signal system, transmitting a predetermined frequency, a receiving device, means for operating said device substantially at a speed proportional to said frequency, control means for varying said speed, a generator of alternating electromotive force having a frequency proportional to the first-mentioned frequency, a second generator of electromotive force having a frequency proportional to said speed and 90° out of phase from the electromotive force of the first generator when the two generators have the same frequency, and means for causing said control means to vary said speed in one direction when said phase displacement increases and in another direction when the phase displacement decreases.

19. In a signal system, transmitting a predetermined frequency, a receiving device, means for operating said device substantially at a constant speed proportional to said frequency, control means for varying said speed, a generator of alternating electromotive force having a frequency proportional to the first-mentioned frequency, a second generator of electromotive force having a frequency proportional to said speed and 90° out of phase from the electromotive force of the first generator when the two generators have the same frequency, and means for causing said control means to increase said speed when said phase displacement increases and to decrease the speed when the phase displacement decreases.

20. In a signal system, transmitting a predetermined frequency, a receiving device, a motor for operating said device substantially at a speed proportional to said frequency, control means for varying said speed, a generator of alternating electromotive force maintained by the signals at a frequency proportional to the first-mentioned frequency, a second generator of electromotive force maintained by said motor at a frequency proportional to said speed, with its electromotive force 90° out of phase from the electromotive force of the first generator when the two generators have the same frequency, and means for causing said control means to increase said speed when said phase displacement increases and to decrease the speed when the phase displacement decreases.

RICHARD E. MATHES.
